Patented June 4, 1957

180,416

COMBINED PUMP AND CAP FOR A CONTAINER

Herbert M. Piker, Wyoming, Ohio, assignor to Hamilton-Skotch Corporation, a corporation of Ohio

Application May 31, 1956, Serial No. 41,703

Term of patent 14 years

(Cl. D2—2)

Fig. 1 is a side view of a combined pump and cap for a container embodying my new design.

Fig. 2 is a similar view thereof taken at right angles to the view of Fig. 1.

Fig. 3 is a plan view thereof.

I claim:

The ornamental design for a combined pump and cap for a container, as shown.
